XR D 11,986

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,986, dated October 26, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics.

It consists in the novel grouping and configuration of figures hereinafter more fully described.

The accompanying photograph illustrates a face view of wall-paper having my new design.

The most prominent figure of the design is a large central fan, A, bearing near the upper left-hand corner the representation of a bird, a, below the same an arched border, b, and near the right-hand corner circular ornaments c, scrolls d, and floral ornaments e. Palm-like leaves and flowers g partly cover the fan A.

A bunch, n, of plums is beneath the fan A and joins it to a lower fan, B, of which the two halves o and p are shown—that is to say, when the design is "matched" the half o abuts against the half p of the next piece of wall-paper, thereby producing the fan B. This lower fan is above an arched stripe, h, ornamented with peculiar-shaped scrolls i, partly-circular ornaments j, and flowers l. Palm-like leaves m also cover in part the lower portion of fan B.

Between the fans A, B is also interposed a circular ornament, D, having checkered groundwork, and a segmental figure, E, having its groundwork divided by radial lines into several fields, all of which are ornamented with different geometrical figures.

A ball-shaped figure, s, projects from the side of the part p of fan B.

Below the figure n and the parts o and p of two fans, B, is a richly-flowering stem, F, as

shown, which, on the matched design, appears to spring from the fan A and to extend beneath the several fans, so as to embellish the groundwork between the fans.

45

The entire design has a luxurious tropical effect, and can be produced to advantage in a variety of colors.

I claim—

1. The design for a wall-paper, consisting of the figure A of a fan with the ornamental figures a, b, c, d, and e thereon, substantially as shown.

2. The design for a wall-paper, consisting of the fan-shaped figure A and of the leaves and flowers g, partly covering the same, substantially as shown.

3. The design for a wall-paper, consisting of the figure B of a fan with the ornamental figures h, i, j, and l thereon, substantially as shown.

4. The design for a wall-paper, consisting of the fan-shaped figure B and leaves m, partly covering the same, substantially as shown.

5. The design for a wall-paper, consisting of the figures A, B, and n, substantially as shown.

6. The design for a wall-paper, consisting of the figures A, B, D, and E, substantially as shown.

7. The design for a wall-paper, consisting of the figures B and s, substantially as shown.

8. The design for a wall-paper, consisting of the figures A, B, and F, substantially as shown.

9. The design for a wall-paper, consisting of the figures A, B, D, E, F, g, m, n, and s, substantially as shown.

EDUARD LEISSNER.
